L. P. DIXON & G. E. POST.
BINDER FRAME.
APPLICATION FILED JUNE 2, 1911.

1,081,297.

Patented Dec. 16, 1913.

COLUMBIA PLANOGRAPH CO., WASHINGTON, D. C.

UNITED STATES PATENT OFFICE.

LAURENS P. DIXON, OF NEW YORK, AND GEORGE E. POST, OF BROOKLYN, NEW YORK,
ASSIGNORS TO THE FIRM OF ANDERSON & PRIGGE, OF NEW YORK, N. Y.

BINDER-FRAME.

1,081,297.

Specification of Letters Patent.

Patented Dec. 16, 1913.

Application filed June 2, 1911. Serial No. 630,803.

To all whom it may concern:

Be it known that we, LAURENS P. DIXON, a citizen of the United States, and a resident of the city of New York, borough of Manhattan, county and State of New York, and GEORGE E. Post, a citizen of the United States, and a resident of Bay Ridge, borough of Brooklyn, county of Kings, and State of New York, have made and invented 10 certain new and useful Improvements in Binder-Frames, of which the following is a specification.

Our invention relates to an improvement in binder frames adapted to be used in connection with loose-leaf ledgers and the like, the object of the same being to provide an article of this kind which shall be economical to manufacture and assemble, strong, durable and efficient in use, and the parts 20 so constructed and arranged that the binder plates, moving transversely with relation to the back plate, shall be truly and perfectly guided in their travel, in order to operate easily and freely, means being provided to 25 retain them in perfect alinement.

A further object is to so construct the lugs to which the telescopic tubes are secured that they may be easily and readily assembled to the binder plates and without danger 30 of movement thereon.

A further object of the invention is to improve in various ways upon the construction of the frame shown and described in Letters Patent No. 968,138, granted to LAURENS P. DIXON, on August 23, 1910, and with these and other ends in view, our invention consists in certain novel features of construction and combinations of parts 35 as will be hereinafter fully described and 40 pointed out in the claims.

In the accompanying drawing, Figure 1 is a bottom plan view of a binder frame constructed in accordance with our invention. Fig. 2 is a sectional view of the same taken on the line 2—2 of Fig. 1. Fig. 3 is a transverse sectional view taken on the line 3—3 of Fig. 1. Fig. 4 is a detached view in perspective of one of the retaining lugs. Fig. 5 is a similar view of a guide block, and Fig. 6 is a similar view of one 45 of the guide rods.

Referring to the drawings, 10 represents the back of the binder, curved somewhat in cross-section, and preferably covered with cloth or fabric to lend thereto a neat and

attractive appearance, this back being provided with the downwardly extending ends 12, through one of which is formed the opening 13 for the entrance of a key to engage with the squared end of the threaded shaft 14. This shaft 14, as in similar structures, is provided at one end 15 with a right-hand thread, and at its opposite end 16 with a left-hand thread, the shaft being journaled near its extreme ends in the guide blocks 17, 60 one of these blocks being clearly shown in perspective in Fig. 5. These blocks serve two purposes, viz., to not only form a bearing for the rotating shaft 14, but also as a guide to nicely direct the movement of the guide rods 18 when traveling with the binder plates 19 to which they are attached in a direction toward or away from the back 10. These guide blocks 17 are each provided with grooves or recesses 20, in 65 which fit and move one side or flange of the guide rods 18, these rods being preferably formed in the shape of an angle iron, the side 21, which fits into the groove 20, being recessed to form a shoulder 22 to strike 70 against the end of the block 17 and thereby limit the lateral or transverse movement or travel of the rods and binder plates 19 to which they are secured, as hereinafter described. The blocks 17 are also each recessed in their lower or under side, and in 75 each fits the section 23, the lower side of which lies flush with the under side of the block 17, when the parts are assembled, and its upper side hollowed out to correspond 80 with the rounded upper side of the recess, the same forming a circular opening 24, in which is fitted or journaled the end of the threaded rod or shaft 14, the latter being slightly cut away as illustrated at 25, Fig. 95 2, where it is fitted into the block 17, these means preventing any endwise movement of said shaft. The blocks 17 are secured to the back plate 10 by means of the screws or rivets 26 passing through the openings 27 formed 100 in said blocks, and into the back plate, where, if desired, the ends of said rivets or screws may be upset. These guide rods 18, or those shown and described as being in the form of angle irons, may be of any desired shape, but the shape thereof shown and used in connection with the guide blocks 17, constructed and arranged as described, we believe at the present time to be the better form of construction, particularly be- 105 110

cause such avoid the necessity of the accurate fitting of the parts necessary in other forms of binder, in order to have the device work freely and smoothly. These guide rods are riveted or otherwise secured to the binder plates 19, and, traveling in the grooved or slotted blocks 27, guide or direct said binder plates in their lateral or transverse movement with relation to the back plate, the several parts being held in proper alinement and preventing any twisting movement thereof. These binder plates, preferably shaped as illustrated, are provided with the blocks 30, illustrated in perspective in Fig. 4, these blocks being provided on one side or surface with the lugs or projections 31, and on the under side with the lug 32. In each of the binder plates 19 are formed openings, through which these lugs 31 pass and upset on their extreme ends against the inner side or surface of said binder plates, the said plates being also provided with openings through which extend the lugs 32, the latter being then bent as illustrated in Fig. 3 to assist in holding the block in place.

We have found in actual practice that by thus forming the block with the two holding lugs on the one side, and the one lug on the under side, said block is tightly and securely held in position against movement or accidental disengagement from the binder plate. Into these several blocks 30 are pinned or otherwise secured the telescopic rods and tubes 40-41, these tubes and rods being used for the same purpose and in the same manner as in the usual form of binder frames, for instance, like those shown and described in the patent, *supra*. Our device is also provided with the traveling nuts 42-43 threaded on the shaft 14, and with which are connected the inner ends of the levers 44, the outer ends thereof being pivoted to the binder plates 19, as has heretofore been commonly done in binder frames of this particular type, and which therefore need no detail description.

It will be understood that when the shaft 14 is rotated, the nuts 42 and 43 will be caused to travel toward or away from each other, the levers 44 causing the binder plates to travel toward or away from each other, and transversely with relation to the back 10, the movement of such being guided by the rods 18 traveling in the grooved stationary blocks 17, the rods 40 at the same time traveling within the tubes 41.

What we claim is:—

1. A binder frame comprising a back; two

blocks formed separate from said back and secured thereto and each of which blocks is provided with two transversely extending open grooves; two binder plates movable toward and from one another and transverse to said back; two guiding members secured to each of said binder plates and the free ends of which slide in the grooves aforesaid; and means for moving said binder plates.

2. A binder frame comprising a back; two blocks formed separately from said back and secured thereto and each of which blocks is provided with two transversely extending open grooves located in opposite sides thereof; two binder plates movable toward and from one another and transverse to said back; two guiding members right angular in cross-section secured to each of said binder plates and the free ends of which slide in the grooves aforesaid and move in contact with the sides of said blocks; and means for moving said binder plates.

3. A binder frame comprising a back; two blocks formed separate from said back and secured thereto and each of which blocks is provided with two transversely extending open grooves and with a bearing in the base thereof; two binder plates movable toward and from one another and transverse to said back; two guiding members secured to each of said binder plates and the free ends of which slide in the grooves aforesaid; a shaft having journal portions adapted to lie within the bearings aforesaid of said blocks and having a right and a left thread formed thereon; a traveling nut upon each of said threaded portions; and links connecting each nut with each of said binder frames.

4. In a binder frame, binder plates movable toward and from one another; blocks secured to each of said binder plates and each of which blocks is provided with a lug upon one face adapted to extend through said binder plate and to be upset upon the inner surface thereof, and with a second lug upon another face adapted to extend through said binder plate and to be bent into contact with the inner surface thereof; and telescoping members, the outer ends of which are secured in said blocks.

Signed at New York, in the county of New York, and State of New York, this first day of June, 1911.

LAURENS P. DIXON.
